HAND RAILING FOR A BATHTUB

Garnet H. Tisdall, Detroit, Mich.

Application October 10, 1957, Serial No. 689,365

2 Claims. (Cl. 4—185)

It is a well-known fact that many persons have been injured, sometimes seriously, when entering or leaving a bathtub, particularly when a bathtub has been made slippery by use of soap. This inherent danger is particularly pronounced in cases of elderly persons or persons weakened by disease.

To eliminate this source of danger, I have devised my railing which is of a kind that may be easily applied either to new bathtubs or to tubs already in use.

A more specific object of my improvement is to provide a railing of such structure as to impart to it a compactness in design, adaptability for easy installation without the need of any special tools, sturdiness of structure, and a stability against deflection from its serviceable position.

I shall now describe my improvement with reference to the accompanying drawings in which:

Fig. 1 is a front elevational view of a bathtub and a railing mounted thereon, the view illustrating the use of the railing by disclosing the person of a child climbing out of the bathtub;

Fig. 2 is a perspective view of one of two units of which the railing is composed;

Fig. 3 is a side elevational view of said unit;

Fig. 4 is an enlarged clamping member adapted to be applied against the inside surface of the bathtub, the member being one of a plurality of elements by means of which the railing is attached to the respective bathtub;

Fig. 5 is an enlarged sectional view of an adjustable clamping member designed to work with the member shown in Fig. 4;

Fig. 6 is a sectional view on line 6—6 of Fig. 5;

Fig. 7 is a front elevational view of a modified railing mounted for use on a bathtub;

Fig. 8 is an enlarged front elevational view of one unit of said modified railing;

Fig. 9 is a view on line 9—9 of Fig. 8;

Fig. 10 is a view on line 10—10 of Fig. 8;

Fig. 11 is a sectional view on line 11—11 of Fig. 9;

Fig. 12 is a sectional view on line 12—12 of Fig. 9;

Fig. 13 is a sectional view on line 13—13 of Fig. 10;

Fig. 14 is a sectional view on line 14—14 of Fig. 9.

Similar numerals refer to similar parts throughout the several views.

A bathtub upon which the railing is to be mounted is generally identified by numeral 10. The front or front panel of the bathtub is marked 11, while a horizontal ledge or top of the bathtub is marked 12. The railing is composed of two identical units 13 opposed to each other in a spaced and symmetrical arrangement.

Each unit includes a member made of a single length of stock, such as a tube or rod, the member being looped upon itself in a hairpin turn so as to produce two parallel legs 14 and 14a. The legs, which are joined by the looped portion 15, are not of the same length, said leg 14a being shorter than the opposite leg 14. The spacing between the legs is such that the unit may be applied

2

from above to straddle the front wall of the bathtub. The front wall includes said panel 11, the top ledge 12, and an inner panel 17 which, in part, defines the space to be occupied by the person using the bathtub.

5 One of the legs, the shorter one 14a, carries a metal plate 17a which is welded to the lower end of said leg, as shown at 18, while the front portion of the plate supports a rubber pad 18a which is suitably cemented or otherwise affixed to said plate. The pad is adapted to 10 be brought to bear against the front wall of the tub from inside of the tub. The opposite leg 14, which is disposed vertically along the front panel 11 of the bathtub, is provided with two clamping members generally marked 19. Each consists of a threaded bolt 20 which at one 15 end is secured to said leg 14, preferably by being welded. This is shown in Fig. 5, in which case the unit 13 includes a solid rod 21.

Axially mounted on the bolt is a circular, convex-concave member or cup 22 which has a threaded central aperture 23 for engagement with said bolt 20. The open or concave portion of the cup includes an annular rim 25 which is provided with a recess 25 for reception of a metal disk 26. The disk serves as a base for support of a rubber pad 27 which is cemented or otherwise attached thereto. Seated on the bolt between the cup and the rod 21, and bearing against said cup, is a nut 28.

It will be noted that the leg 14 is provided with two such clamping members 19, and that one of them is aligned horizontally with the clamping member on the shorter leg 14a, while the other member 19 is carried by said leg 14 at its lower end which terminates at a level above the floor "F" adjoining the bathtub 10.

The two legs 14 and 14a are joined by a transverse bar 29 which is disposed horizontally above the ledge 12 at 35 a level just below the looped portion 15 of the unit 13. Connected to the bar 29 by means of a T-joint 30 is a laterally-extending brace 31 which is made in the form of a rod terminating with a cup-shaped anchoring device 32. The latter may consist of a vacuum cup or some suitable 40 device adapted to be permanently attached to the ledge 12.

The two units 13 are to be mounted at such spacing from each other as to afford sufficient room therebetween for a person to climb over the ledge 12 of the bathtub. The looped portions of the units are to be disposed parallel to each other to provide means for a manual grasp of the railing by a person desiring to step over the front wall of the bathtub. The legs of the respective unit 13 are secured to the front wall of the bathtub in the manner shown in the drawings. This is effected by means 50 of the clamping member on the shorter leg, said member bearing against the front wall of the bathtub from inside, and by means of the two clamping members 19 which bear against the wall from outside, that is, against the front panel 11. As each of the cups of the clamping members 19 is mounted upon the threaded bolt and may be rotated upon said bolt, the cup may be caused, by rotation thereof, to be brought into a tight frictional contact with said front panel 11 and to bring into similar 55 tight frictional contact the clamping member on the shorter leg against the front wall of the tub from inside the bathtub.

In its modified form shown in Figs. 7 to 14, the railing is also composed of two units. Each unit, as shown best 60 in Figs. 8 and 9, is composed of a standard 40 which consists of a tubular member bent upon itself so as to include two parallel legs, a shorter one 41 and a longer one 42, the two legs being joined by an integrally-formed loop 43. The legs are spaced from each other so as to straddle one side wall of the bathtub, which wall includes a front panel 44, a flat top portion 45, and an inner panel 46.

Pivotedly mounted within the lower end of the shorter leg 41, by means of a bolt 47, is a flat ear 48 which supports a clamping plate 49 bearing against the front panel 46 within the inner space of the tub. The opposite or the longer leg 42 is provided with two clamps. Each includes a cylindrical member 50 radially secured to the leg 42 and a stem 51 which is threaded into the member 50 and carries at its opposite end a disk 52 adapted to bear against said front panel 44. A nut 53 upon the stem 51 serves as a means of effecting a tight clamping grip of the legs upon the wall of the tub.

It will be noted that the leg 42 is provided with two such clamps, one being located directly opposite the plate 49 carried by the shorter leg 41.

At a level just above the top 45 of the wall of the bathtub, the two legs of the standard are connected by a horizontal rod 54 which at each end is held in place by a bolt 55 passing diametrically through one of the respective legs, as shown in Fig. 14.

Disposed at right angle to the plane of the two legs 41 and 42 is another or auxiliary railing generally marked 56. This consists of a tube having a vertical portion 57 which at the lower end is provided with a flat disk 58 resting on top 45 of the tub's wall. Just above the top of said disk, the vertical portion 57 is provided with a diametrical aperture for connection to the above-named rod 54. At a level spaced from the top of the loop 43, the vertical portion 57 curves at right angle away from the plane of the standard, slopes downwardly as shown at 59, and is bent upon itself in a loop 59a. The outer end of said railing 56 consists of a horizontally-disposed portion 60 which is secured to the top 45 of the tub.

This is effected by means of an inverted U-shaped anchoring device which, like the standard 49, includes two legs, these being marked 61 and 62, respectively. The first of said legs is provided with a pivotally-mounted clamping plate 63. More specifically, the lower end of the leg 62 contains a plug 64 which at its outer end includes a bifurcated eye 65. The clamping plate 63 is secured to said eye 65 by means of a short ear 66.

The two legs 61 and 62 are but parts of one length of a tubular stock bent upon itself in a hairpin loop. The looped portion, identified by numeral 66, engages the horizontal length 69 of the railing 56 by passing through a diametrical hole in said portion 69. A vertical bolt 68, threaded diametrically through said horizontal portion 60, terminates with a disk 69 which bears against the upper surface 45 of the wall of the tub.

As shown in the drawings, the upper portions of the U-shaped standards 49 rise above the top of the wall to a sufficient height to allow a person entering the tub or

leaving it to grasp the looped portions of the two standards. The laterally-extending railings marked 56 will be found helpful to a person still seated in the tub but desiring to rise to a standing position.

After having described my railing, what I wish to claim is as follows:

1. In combination with a side wall of a bathtub, a railing consisting of a single length of elongated stock formed into a U-shaped standard including a looped top and two parallel legs disposed vertically and straddling the wall, a pad on one leg bearing against one side of the wall, adjustable clamp means mounted on the other leg and opposed to said pad and bearing against the opposite side of the wall, a transverse bar joining the two legs at a level above the top portion of the wall about one-half of the length of the standard including its looped end extending above the top of the wall of the bathtub, an inverted U-shaped member straddling said wall at a point spaced from said standard, the U-shaped member including two legs clamped to said wall, and a looped portion disposed on top thereof, and a tubular member at one end secured to the transverse bar of the standard and secured at the other end to the looped portion of the shaped member, said tubular member including a portion disposed in a spaced relation above the top of said wall.

2. In combination with a side wall of a bathtub, a railing consisting of a single length of elongated stock formed into a U-shaped standard including a looped top and two parallel legs disposed vertically and straddling the wall, a pad on one leg bearing against one side of the wall, adjustable clamp means mounted on the other leg and opposed to said pad and bearing against the opposite side of the wall, a transverse bar joining the two legs at a level above the top portion of the wall about one-half of the length of the standard including its looped end extending above the top of the wall of the bathtub, a U-shaped member mounted on the wall in a spaced relation to the standard, the U-shaped member including two legs straddling the wall and secured thereto by clamping means on said legs, and a portion looped over the top of said wall, and a tubular rail at one end connected to the transverse bar, the railing first rising upwardly, then sloping towards said U-shaped member, and being connected to the looped portion thereof.
